UNITED STATES PATENT OFFICE.

MAXIMILIAN BACHMANN, OF PHILADELPHIA, PENNSYLVANIA, ASSIGNOR TO HARPER FORREST SMITH, SR., OF SAME PLACE.

DESIGN FOR A BUST.

SPECIFICATION forming part of Design No. 18,854, dated January 15, 1889.

Application filed October 4, 1888. Serial No. 287,239. Term of patent 7 years.

To all whom it may concern:

Be it known that I, MAXIMILIAN BACHMANN, a citizen of Berlin, and a subject of the Emperor of Germany, but now residing in the city and county of Philadelphia, State of Pennsylvania, have invented and produced a new and original Design for a Bust, of which the following is a specification, reference being had to the accompanying photograph, forming part thereof.

The bust is that of a Saracen or Moorish prince. The face has a fierce expression and a short growth of beard and mustache. On the head is a chased helmet, on the top of which is an ornament. Around the base of the helmet, turban fashion, is wound a scarf, the fringe from the end of which is exposed on the right side of said scarf. On the front of this scarf is a crescent. Hanging from the helmet is the representation of a piece of chain armor, which, leaving the face exposed, is joined under the neck by a jewel and hangs in points on his breast. Under the armor is seen a portion of a striped garment covering the chest. Over this is thrown his mantle, also striped and fringed, some of the fringe of which is seen on the right shoulder. From under his mantle appears the handle of a dagger studded with jewels and tipped with a chased ornament. Across the chest run three tasseled cords holding the mantle in place. The base is made to resemble alligator-skin, and is the same all around on all four sides. On the back of the figure, from under the helmet, apparently hiding the chain armor, hangs a veil, fringed, a small portion of the fringed end of it falling over the left shoulder in front.

What I claim as my invention, and desire to protect by Letters Patent, is—

The design for the bust of a Saracen, having the shape, ornamentation, and characteristic features herein shown and described.

MAXIMILIAN BACHMANN.
